CLAIM

The ornamental design for a home audio player/amplifier, as shown and described.

DESCRIPTION

FIG. 1 is a front view showing our new home audio player/amplifier;

FIG. 2 is a side view thereof;

FIG. 3 is another side view thereof;

FIG. 4 is a back view thereof;

FIG. 5 is a top view thereof;

FIG. 6 is a bottom view thereof; and,

FIG. 7 is a perspective view thereof.

The areas in broken lines are for illustrative purposes only and form no part of the claimed design.
